UNITED STATES PATENT OFFICE.

WILHELM MÜNDER, OF EISLINGEN, GERMANY, ASSIGNEE, BY MESNE ASSIGNMENTS,
TO THE CHEMICAL FOUNDATION, INC., A CORPORATION OF DELAWARE.

METHOD OF AND APPARATUS FOR PRODUCING HYDROCARBONS.

Application filed December 31, 1915. Serial No. 69,590.

To all whom it may concern:

Be it known that WILHELM MÜNDER, chemist, residing at Eislingen, in the Kingdom of Wurttemberg, Germany, has invented
5 a certain new and useful Improved Method of and Apparatus for Producing Hydrocarbons, of which the following is a specification.

My invention relates to an improved
10 method of and apparatus for producing light hydrocarbons free from sulphur, asphalt and water from heavy mineral oils and their residual products, such as petroleum-pitch, saponifiable oil and the like,
15 which latter products may contain a large amount of sulphur, asphalt and water and no components boiling below a temperature of 300° C.

According to the present invention my
20 improved method is performed by using two distilling processes at different pressures.

In opposition to the prior processes it is possible with my novel method to obtain in a continuous cycle of operations pure hydrocarbons boiling at a temperature between 40 and 280° C. even with such residues which contain up to 50% of water, without a previous freeing or depriving of said residues from water being necessary, whilst this is
25 quite unavoidable in the methods known up to present. The hydrocarbons obtained with my improved process are free from sulphur and asphalt, even on using residues containing a high percentage of sulphur and asphalt.

The process forming the object of the present invention is carried out in such a way that first the raw or crude materials to be treated are subjected to distillation process under the
40 influence of a small excess of pressure above the atmospheric pressure. It appears that by employing a small overpressure a product free from asphalt and water can be obtained, said product being almost free of sulphur, because, the sulphur compounds are decomposed and escape in form of sulphuretted hydrogen, whilst all substances containing asphalt remain in the reacting vessel in the
45 form of coke.

50 The product resulting from said first treatment, which sometimes contains small quantities of sulphur, is, at the same rate as it enters into the apparatus, drawn off from said apparatus by a pump and led into a horizontal autoclave, so that the process is,

continuous, with respect to the gaseous products, from the very starting of the treatment of the raw or crude material up to the obtaining of the final product. In the autoclave the resulting product, in order to further split up the light hydrocarbons already obtained into quite light hydrocarbons and to remove the last sulphur compounds, is preferably heated so as to afford a relatively high pressure of say 15 atmospheres, and subsequently, by automatic opening of the valve adjusted to a corresponding pressure, i. e. 15 atmospheres, said product is slowly and uninterruptedly distilled at the same pressure. The temperature is preferably maintained between 300 and 400° C. The last sulphur compounds are decomposed and are drawn off in the form of sulphuretted hydrogen. The yield of light hydrocarbons free from sulphur, asphalt and water amounts to about 90% of the original product. The greater part of these hydrocarbons boils at a temperature of 40°-200° C., the boiling temperature of the other hydrocarbons being 200-280° C.

80 The working in both steps of the process, i. e. the distillation at a low pressure, as well as the distillation carried out at a comparatively high pressure, is continuous providing two stills for the preliminary treatment are employed so that when it becomes necessary to remove the coke from the one the other may carry on the operation.

In the accompanying drawing forming a part of this specification an apparatus for carrying out the process forming the object of my invention is represented.

The raw or crude material flows from a container 1 through a pipe 2 provided with a check-valve or an obturator 3 into the distilling vessel 4 heated to about 300° C. The container 1 is arranged about 6 meters above the vessel. The raw material flowing into the vessel is vaporized and the vapors as well as the aqueous vapour which may have been generated from the water contained in the raw material are led by a pipe 5 into a cooler or condenser 6 in which they are condensed. This operation may be accelerated by slightly exhausting the vapours in question. The very fluid condensed product gathered in a receiver 7 is at once separated from the water and can be segregated or decanted from said water by means of a siphon 18 and the like. Even when the raw

or crude material contains 5-8% of sulphur the distilled product is nearly free from sulphur, whilst the whole asphalt soluble in benzin, ether and alcohol remains in 5 the distilling or cracking vessel 4 in form of coke. By using distilling vessels which are alternately operated and cleaned, the method becomes quite continuous.

The products of distillation free from 10 water and asphalt which still contain traces of sulphur, in order to remove the remaining sulphur and for the sake of further decomposition or splitting up into quite light hydrocarbons, are led by means of a pump 8 15 through a pipe 9 provided with a non-return valve 10 into a horizontal autoclave 11 having an outlet-pipe 14, and in said autoclave 11 said products of distillation are brought to an overpressure of about 15 atmospheres 20 by being heated to 300°-400°. As soon as this pressure is reached, the vapours are conducted into a cooler or condenser 16 and are condensed therein. The condensed product is then gathered in a receiver 17. 25 Also this step of my improved method or process is rendered continuous by inserting the non-return valve 10 into the filling-tube 9 in the path from the vessel 7 to the autoclave 11, because a segregation of coke in 30 the autoclave no longer takes place in consequence of the preliminary treatment referred to.

The obtained condensed products are free from water, sulphur and asphalt and, as a 35 rule, have a boiling temperature of 40°-200°. Further, said products of condensation are free from the well known odour or smell. Moreover, said products even after being kept for a number of years show no subsequent darkening after refining.

Having thus described my invention, what I claim and desire to secure by Letters Patent of the United States is:—

1. The process for the production of light 45 hydrocarbons free from sulphur, asphalt and

water, which comprises subjecting heavy hydrocarbons and their residual products to a first distillation at about atmospheric pressure, condensing the vapor, and then heating, with continuous distillation, in an autoclave under a pressure above atmospheric. 50

2. The process for the production of light hydrocarbons free from sulphur, asphalt and water, which comprises distilling heavy hydrocarbons and their residual products at 55 a temperature of about 300° C. and at a pressure of about one atmosphere, condensing the vapor, and then heating, with continuous distillation, in an autoclave under a pressure above atmospheric. 60

3. The process for the production of light hydrocarbons free from sulphur, asphalt and water, which comprises distilling heavy hydrocarbons and their residual products at a temperature of about 300° C. and at a 65 pressure of about one atmosphere, condensing the vapor, and at once continuously distilling in an autoclave at a temperature of about 300° C. to about 400° C. and at a pressure of about 15 atmospheres, and finally 70 condensing the vapors.

4. An apparatus for obtaining light hydrocarbons free from sulphur, asphalt and water, consisting of a distilling vessel, a container raised above and connected with the 75 distilling vessel by a valve pipe, a condenser connected with said distilling vessel, a receiver connected with the condenser and adapted with a siphon for the removal of the condensed water, an autoclave with a 80 valve pipe connecting said autoclave with said receiver, a pump in said pipe, and a condenser connected with said autoclave.

In testimony whereof I affixed my signature in presence of two witnesses.

WILHELM MÜNDER.
